(57) **CLAIM**

The ornamental design for diamond with inscribed cross, as shown and described.

DESCRIPTION

FIG. 1 is a top view of a diamond with inscribed cross showing my new design;

FIG. 2 is a front view of FIG. 1.

FIG. 3 is a rear view of FIG. 1; and,

FIG. 4 is a side view of FIG. 1, with the other side being symmetrical.

The broken line showing of a setting in FIGS. 2, 3 and 4 is included for the purpose of illustrating environmental matter and forms no part of the claimed design.
